UNITED STATES PATENT OFFICE.

NELS PAULSEN AND MERTON A. COLER, OF CHICAGO, ILLINOIS.

SMOKING PIPE.

Application filed July 2, 1924. Serial No. 723,749.

To all whom it may concern:

Be it known that we, NELS PAULSEN and MERTON A. COLER, citizens of the United States, residing at Chicago, in the county 5 of Cook and State of Illinois, have invented certain new and useful Improvements in a Smoking Pipe, of which the following is a specification.

This invention relates to an improved 10 smoking pipe and it belongs to that class of inventions wherein devices are used in association with the pipe for collecting and preventing the passage of nicotine laden fluid through the stem of the pipe.

15 It is our object to generally improve upon devices of this class by providing a receptacle for collecting the tobacco juices wherein means is provided for cleaning the walls of the receptacle and for removing the juice 20 deposit therefrom.

It is the feature of the invention to construct the aforesaid means in the form of a double headed plunger wherein the inner head constitutes the cleaning means and the 25 means in the other head forms the closure for the receptacle.

It is also a feature of the invention to have a pivoted lever for actuating the plunger and having this lever disposed in an out 30 of the way position but permitting it to be readily grasped for actuating the plunger.

Other features and advantages of this invention will become apparent from the following description and drawing.

35 In the accompanying drawing forming a part of the specification in which like numerals are employed to designate like parts throughout the same:

Figure 1 is a central longitudinal section 40 through a pipe constructed in accordance with the present invention.

Figure 2 is an enlarged transverse section taken on the line 2—2 of Figure 1.

Figure 3 is a view like Figure 1, but 45 showing slightly different embodiment of the invention.

Referring now to the drawing in detail, the letter B designates the usual tobacco receiving bowl, the letter S indicates the 50 common stem which is attached thereto. In the present instance the bottom of the bowl is recessed to accommodate an open ended cylinder or sleeve 1 which is fitted into the recess. The bottom of the bowl B is provided with a smoke discharge port which

communicates with an opening formed in the sleeve to permit passage of the smoke through the cylinder and then through the passage in the stem. Slidably mounted in this cylinder is a plunger which, as before 60 stated, is equipped with two heads 2 and 3 respectively. The head 2 is at the outer end and is shaped in the manner shown to follow the external contour of the bottom of the bowl so that the new device will not detract 65 from the usual symmetrical appearance of the latter. The head 3 is of discular formation and is provided with a central opening which is in alignment with the smoke passage of the stem S. A rod 4 extends inwardly from the plunger head 3 and is seated in a suitably formed groove in the bottom of the stem. A lever 5 is pivoted to the inner end of the rod and is adapted to serve as a handle for forcing the plunger outwardly to the dotted line position indicated 70 in Figure 1. At its free end, the lever is provided with opposed ears which straddle the plunger rod. The extremity of the lever may be shaped as indicated at 7 to permit the finger nail or tip of the finger to be engaged therewith for swinging the lever to operative position. It will be observed that the plunger heads 2 and 3 are of a 75 diameter equal to the internal diameter of the sleeve 1. The head 3 is thus given the function of a cleaner since as the plunger is slid outwardly, it scrapes the walls of the cylinder.

From the foregoing description it will be 80 obvious that we have provided a receptacle at the bottom of the tobacco receiving bowl for collecting tobacco laden juices. Unless the cylinder is more than half full, the 85 juices will be effectively retained therein and will be prevented from passing through the smoke passage of the stem. After each smoke or whenever desired, the user may swing the lever 5 to the dotted line position, at which time it serves as a handle 90 for forcing the plunger outwardly to the dotted line position indicated in Figure 1, thus discharging the juices and cleaning the 95 walls of the cylinder.

Directing attention now to Figure 3, it 100 will be seen that a slightly different embodiment of the invention is shown. Here, the cylinder 1^a is substantially the same as that shown and described and it is fitted into the recess formed in the bottom of the bowl. 110

Also, the plunger is composed of inner and outer heads 2^a and 3^a respectively, the last named head being apertured at its center to permit passage of smoke therethrough and into the smoke passage of the stem. The heads instead of being connected together by a rigid single rod are connected together by a pair of links 8. The means for withdrawing the plunger in this instance comprises an arcuate lever 9 which is pivoted to the bowl as at 10, is secured at its lower end to the plunger head 2^a and has its extremity fashioned to provide a spring catch 11 for reception in a recess formed in the external surface of the bottom of the bowl. It is obvious that by disengaging the catch and swinging the lever outwardly, the plunger will be withdrawn for removing the juice content from the cylinder. It is evident from the foregoing description and drawing that we have evolved and produced a novel invention for separating the undesirable tobacco juices from the smoke and collecting these juices in a receptacle from which they may be discharged at any desired moment. Thus, the tobacco juices will not run through the stem and get into the mouth of the smoker as is usual.

While we have shown and described the preferred embodiment of the invention, we wish it to be understood that minor changes coming within the scope of the adjoined claims may be resorted to if desired.

Having thus described the invention, what we claim is:

1. A smoking pipe comprising a body including a tobacco receiving bowl and a bored stem extending laterally therefrom, said stem and bowl being recessed; an open ended cylinder fitted into said recess, a plunger 40 slidably mounted in said cylinder and provided at its opposite ends with heads closing the opposite ends of the cylinder, one of said heads being provided with a central aperture in alignment with the bore of said stem, and a pivotally mounted lever having connection with the plunger for sliding it in or out of said cylinder. 45

2. A smoking pipe comprising a body including a tobacco receiving bowl and laterally directed bored stem, said body being provided with a recess forming a socket, an open ended cylinder fitted into said socket, a plunger mounted slidably in said cylinder and including a pair of spaced heads, the inner head being of discular formation and provided with a central aperture in alignment with the bore of said stem, a rod connected to said plunger, and a lever pivotally connected at one end to the inner end of 55 said rod, said lever being swingable into a recess formed in the bottom of said stem. 60

In testimony whereof we affix our signatures:

NELS PAULSEN.
MERTON A. COLER.
